UNITED STATES PATENT OFFICE.

GEORGE M. LORTZ, OF UTICA, NEW YORK.

METALLIC COT-BEDSTEAD.

SPECIFICATION forming part of Letters Patent No. 431,602, dated July 8, 1890.

Application filed January 20, 1890. Serial No. 337,448. (No model.)

To all whom it may concern:

Be it known that I, GEORGE M. LORTZ, a citizen of the United States, residing at Utica, in the county of Oneida and State of New York, have invented certain new and useful Improvements in Metallic Cot-Bedsteads; and I do declare the following to be a full, clear, and exact description of the invention, such as will enable others skilled in the art to which it app pertains to make and use the same, reference being had to the accompanying drawings, and to the letters of reference marked thereon, which form a part of this specification.

The special object of my invention is to make a metallic cot-bedstead whose head and foot pieces shall automatically lock to the body or frame and when unlocked fold beneath it, as hereinafter described.

Figure 1 of the drawings is a bottom perspective view of my bedstead; Fig. 2, a longitudinal vertical section, and Fig. 3 a vertical cross-section.

In the drawings, A represents the body or frame of my bedstead, consisting of the four angle-irons $a a' a' a'$, the former being the sides and the latter the cross-pieces at the head and foot. The side pieces $a a$ have the concave angle underneath the frame A, and the cross-pieces $a' a'$ have the concave angle on the top of said frame. The horizontal sides of the angle-plates $a a'$ are riveted together, while the other sides of plates a project down perpendicularly and those of plates a' extend upwardly in a vertical plane.

The head and foot pieces B B are formed of narrow flat plates b , bent at $b' b'$, so as to form perpendicular leg-posts b^2 , and braced by the spacing-rod $b^3 b^4 b^5$. To the rod b^3 and the inside of the sides $a a$ are pivoted the connecting-bars C C, while to the braces a^2 and the inside of the end pieces B B are pivoted the springs D D, which are provided with the projection d , bent at $d' d'$, so as to be pressed out as they pass up through holes

a^3 in the sides a and then spring over the top 45 of said sides, thus automatically locking the end pieces B B to the frame A, as clearly shown in Fig. 3 of the drawings.

In order to close the bedstead, I take hold of each side and press inwardly against the 50 springs D D with my thumb, while at the same time I slightly raise the sides $a a$. Then the end pieces will readily disconnect from the sides and fold under the frame A.

By means of an angle-plate E at one end of 55 the bedstead and two straight plates F F, the latter riveted to plate E and to one of the angle-plates $a' a'$, I hold securely the ends of a steel-wire mattress G. One plate F is made fast to the angle-plate a' and the other to the 60 angle-plate E.

The plates E F are provided with female threads to receive the adjusting and straining screws H H, which are swiveled in the angle-plate a' , so as to stretch the mattress G 65 as much as may be desired at any time.

Having thus described all that is necessary to a full understanding of my invention, what I claim as new, and desire to protect by Letters Patent, is—

A cot-bedstead having the angle-iron sides $a a$, with holes $a^3 a^3$ near their ends and connected by the rods $a^2 a^2$, in combination with head and foot pieces B B, having cross-rods $b^3 b^4 b^5$, the said sides $a a$ and pieces B B being connected by the pivoted bars C C and pivoted springs D D, and said springs being provided with projections $d d$, adapted to pass up through holes a^3 in the sides a and by means of the inclines d' to spring on and off 80 the sides a , as described.

In testimony whereof I affix my signature in presence of two witnesses.

GEORGE M. LORTZ.
